No. 882,671.

PATENTED MAR. 24, 1908.

G. H. FORSYTH,
METAL WINDOW CONSTRUCTION.
APPLICATION FILED APR. 24, 1905.

UNITED STATES PATENT OFFICE.

GEORGE H. FORSYTH, OF CHICAGO, ILLINOIS.

METAL WINDOW CONSTRUCTION.

No. 882,671.

Specification of Letters Patent. Patented March 24, 1908.

Application filed April 24, 1905. Serial No. 257,151.

To all whom it may concern:

Be it known that I, GEORGE H. FORSYTH, a citizen of the United States, residing at Chicago, in the county of Cook and State of Illinois, have invented certain new and useful Improvements in Metal Window Constructions, of which the following is a specification.

My invention relates to metal window constructions; and has reference more particularly to a construction of window frame or casing and sash designed to afford an elastic or yielding engagement between the sash and its frame or casing guides, so as to produce a practically dust-proof and anti-rattling fit between said parts; a further object of the invention being to allow adjustability in the plane of the sash between the latter and the casing or casing guides.

According to my present invention, the yielding or elastic fit between the sash and the casing guides is secured wholly or partially by making the guide itself yielding or elastic, either in a direction transversely of the sash or parallel with the sash, or both.

My invention also relates to a novel means for securing the glass in the sash, according to which the sash is supported on one side by a glass-holding strip which may constitute an integral extension of the sash frame, and on the other side by a separate strip, suitably united to the latter.

My invention also contemplates an improved manner and means of uniting the stiles and bars of the sash at the corners, such uniting means permitting transverse yielding or elasticity of the stiles, when desired.

My invention, in several approved forms, is illustrated in the accompanying drawing, wherein—

Figure 1 is a front elevational view, broken away intermediate its sides, of a metal sash constructed in accordance with my invention; the same showing on one side a square joint between the stile and bars, and on the other side a mitered joint between said parts; Fig. 2 is a top edge view of Fig. 1; Fig. 3 is a left hand edge view of Fig. 1; Fig. 4 is a right hand edge view of Fig. 1; partly broken out; Figs. 5, 6 and 7 illustrate various forms and constructions of glass-holding means; and Figs. 8 to 12, inclusive, are cross-sectional detail views, illustrating various forms of transversely elastic casing guides; Fig. 9 showing the same coöperat-

ing with a non-elastic sash member, and the remaining figures showing guides coöperating with transversely elastic sash members.

Referring to the drawing, 15 and 15^a may designate, as entireties, the stiles, and 16 the bars of a hollow metal sash frame, containing the glass 17. The bars 16 are preferably closed at their upper and lower edges, respectively, excepting at their ends to approximately the extent of the width of the underlying stiles 15, where they are left open to afford transverse elasticity to the stiles from top to bottom of the sash frame. The stile 15 is preferably open throughout the entire extent of its outer edge, as shown in Fig. 3; while the stile 15^a has a closed outer edge, as shown in Fig. 4. It is to be understood that in practice the sash may have both stiles formed with open or with closed outer edges, as desired; the two constructions being shown in connection with a single sash merely for the purpose of condensing the illustration.

Referring first to the means which I have devised for uniting the sash frame members at the corners, 18 designates elbow-shaped cleats which are preferably formed of sheet metal suitably bent to provide parallel side walls 18^a and an inner rectangular transverse wall 18^b. Said connecting members are securely riveted by their side walls to the inner surfaces of the parallel face members of the stile 15 and bars 16, the riveting being capable of performance by the aid of a suitable mandrel inserted into the hollow connecting member through the open edge or end of the stile. Similar connecting members 18 may be employed to unite the mitered joints between the stile 15^a and the bars 16; but in this case, it being impossible to enter a mandrel on account of the closed edge formation of the stile 15^a, the fastening may be effected by rivets 19 extending entirely through the sash frame, with spacing sleeves 20, surrounding said rivets between the inner walls of the connecting member 18, all as shown in Fig. 4 and at the right of Fig. 1.

Referring next to the means for holding the glass in the sash frame, which is illustrated more particularly in Figs. 5, 6 and 7, and referring first to Fig. 5, it will be observed that in said figure the sheet metal of the stile 15 on one side of the glass is carried inwardly of the edge of the glass and then bent back, forming an integral elastic glass-holding lip 21. The same inner edge of the

stile is further provided with a dovetailed re-entrant portion 22 formed by suitably bending the metal, which portion is preferably filled by a wooden strip 23 against which the 5 edge of the glass seats, the glass being retained in place by a wooden fastening strip 24 secured to the strip 23 as by suitable brads or screws 25 and coöperating with the integral lip 21 in securely holding the glass under 10 spring or tension engagement in the sash.

In Fig. 6 the metal of the stile is projected inwardly and then cut off, forming a single rounded lip 26 engaging the glass, the face members of the stile being united at their inner edges by a channel strip 27 suitably riveted thereto, said channel strip containing a wooden strip 28 secured thereto as by means of pins or brads 29 and screws 29^a, forming an abutment for the edge of the glass 17. 15 Against the opposite side of the glass 17 abuts, preferably under elastic engagement, the metal strip 24, whose offset lower portion 24^a enters into the channel strip 27, where it is held in position by the screws 29^a.

In Fig. 7 the inner margins of the side walls of the stile 15 are bent inwardly, forming the reentrant pocket 32 within which is located the inversely disposed channel filling strip 30, between whose side walls 30^a and the inner walls 32^a of the pocket 32 are inserted the lower offset portions 31^a of the metal strips 31, which preferably engage the glass under spring tension and are held in position by the screws 33, having nuts 33^a within the filling 35 strip 30, whose transverse wall forms a seat for the glass 17. It is evident that the above described means for holding the glass may be employed in connection with the bars as well as with the stiles.

Figs. 8 to 12, inclusive, show various forms of yieldable or elastic casing guides. In Fig. 8, 34 may represent in cross-section a portion of a wooden casing member, fastened to which by the screws 35^a is the elastic guide 45 or rib 35, whose outwardly flaring wings 36 are adapted to elastically engage with the side walls of the stile 15, said walls being preferably yieldable and inclining inwardly, whereby they engage the guide 35 under increased tension.

Fig. 9 shows a casing guide construction comprising a groove 39, one of whose side walls is formed by a detachable metal strip 35^b having an oblique inwardly projecting elastic tongue 37 coöperating with the incline 15^c of a stile member of the non-elastic or closed edge form. This construction provides for transverse elastic engagement between the casing and the sash, as well as for 60 sidewise adjustment therebetween in the plane of the sash.

In Fig. 10, 38 may designate a portion of a hollow metal casing member, the inner wall of which is suitably bent to form a guide space 65 39, one side wall of which is constituted by a

detachable strip 35^b with the elastic sash-contacting tongue 37, said strip being secured in place as by a screw bolt 40 and nut 41. Coöperating with the guide groove thus formed I have shown a hollow stile 15^d, that 70 is transversely elastic, and has the outer margin of one of its face members inwardly bent or inclined, as shown at 42, on substantially the same angle as that of the oblique guide tongue 37 and engaging the latter. When 75 withdrawn from engagement with the casing guide the side walls of said stile preferably flare outwardly; thereby increasing the tension between the latter and the casing guide.

In the construction of Fig. 11, 43 may represent the inner face of the hollow metal casing member, to which is secured, as by means of bolts 44 and 45, the former having a spacing sleeve 46, a bent metal guide 47. One side wall of said guide is formed by an oblique 85 elastic tongue 37^a, while the other is constituted by an S-shaped bend 48, the inner end of which 48^a projects inwardly sufficiently to yieldingly engage the edge of one of the sash members 15^e lying within the stile 15. In 90 this construction the tongue 37^a affords a pressure upon the sash transversely of the latter, while the elastic projection 48^a engaging the edge of the sash member 15^e affords an elastic pressure upon the latter in the direction of its plane. It must be evident that the edges of the stile 15 may be sufficiently extended to enter into engagement with the casing guide 47 as well as the sash member 15^e. In the latter case I prefer to have both 95 the sash member 15^e and the stile 15 flare outwardly; whereas if only the former engage the casing guide the stile is formed either with its side walls parallel to each other or slightly inwardly inclined along their outer 100 margins.

In the construction shown in Fig. 12, the form of the sash guide shown in Fig. 11 is varied so as to substitute for the outwardly pressing member 48 a companion 37^b to the 110 lip 37^a, thus affording transverse or lateral pressure upon both faces of the sash member 15 when entered therebetween.

It will be observed that the inclined lip construction, when constituting one side 115 wall of the casing guide, really affords a combined lateral and widthwise pressure upon the sash, thus tending to insure a good sliding fit between said parts under variations of the sash in both width and thickness relatively 120 to the casing.

While I have shown the sash member engaging the casing guide with one of its inner margins inwardly inclined it must be evident that both of the inner margins thereof might 125 be inclined inwardly, or one might be inclined inwardly and the other outwardly, or both outwardly; without departing from the principle of my invention.

It being evident that the invention as 130

shown and described is capable of variation and modification in respect to details, beyond those herein attempted to be shown, by those skilled in the art to which the invention pertains, I do not limit the latter to the particular forms and constructions disclosed, except to the extent indicated in specific claims.

I claim:

1. The combination with a sash, of a guide therefor, said guide having a lateral sash-confining member provided with an integral angularly-yieldable sash-contacting strip, substantially as described.
2. The combination with a sash, of a guide therefor, said guide having a lateral sash-confining member provided with an integral angularly-yieldable sash-contacting strip normally disposed in a plane oblique to the plane of the sash, substantially as described.
3. The combination with a sash, having a beveled margin, of a guide therefor, said guide having a lateral sash-confining member provided with an integral angularly-yieldable sash-contacting strip lying against said beveled margin of the sash, substantially as described.
4. The combination with a sash, of a lateral guide therefor, said guide having a hollow member provided with an elastic angularly-movable part adapted to engage the sash, substantially as described.
5. The combination with a sash, of a lateral guide therefor, said guide having a hollow member provided with an elastic angularly-movable part adapted to engage the sash and tending to move the latter in its own plane, substantially as described.
6. The combination with a sash, of glass-confining means therefor comprising a non-metallic member supporting the edge of the glass, a metallic strip supporting the glass on one side, and a detachable strip supporting the glass on its other side, substantially as described.
7. The combination with a sash, of glass-confining means therefor comprising a non-metallic member supporting the edge of the glass, a metallic strip supporting the glass on one side, and a detachable metallic strip supporting the glass on its other side, substantially as described.
8. The combination with a metal sash, of glass-confining means therefor comprising a non-metallic member supporting the edge of the glass, a bead integral with the sash supporting the glass, on one side, and a detachable strip supporting the glass on its other side, substantially as described.
9. The combination with a metal sash, of glass-confining means therefor comprising a non-metallic member supporting the edge of the glass, a bead integral with the sash sup-

porting the glass on one side, and a detachable metallic strip supporting the glass on its other side, substantially as described.

65

10. The combination with a sash, of a casing having a transversely elastic sash-guide engaging the outer sides of the sash, substantially as described.

70

11. The combination with a sash, of a casing having a sash-guide, said sash-guide having sash-guiding portions one of which is rigid and the other of which is provided with an elastic element integral therewith, substantially as described.

75

12. The combination with a sash, of a casing having a sash-guide, said sash-guide having sash-guiding portions one of which is rigid and the other of which is provided with an elastic element integral therewith and permitting adjustment of the sash in its own plane, substantially as described.

80

13. The combination with a casing having an elastic sash guide, of a sash having a transversely elastic member engaging said guide, substantially as described.

85

14. The combination with a casing having an elastic sash guide, of a sash having a transversely elastic stile engaging said guide, substantially as described.

90

15. The combination with a casing having an elastic sash guide, of a sash having a transversely elastic member provided with an obliquely disposed element engaging said guide, substantially as described.

95

16. The combination with a casing having an elastic sash guide, of a sash having a transversely elastic stile provided with an obliquely disposed element engaging said guide, substantially as described.

100

17. A sash having a plurality of glass-retaining members, one of said members being elastic and the other being detachable, permitting the glass to be inserted front-wise of the sash, substantially as described.

105

18. A sash having an elastic elbow-shaped connection member uniting a stile and bar at a corner of the sash, substantially as described.

19. A sash having an elbow-shaped connection member uniting a stile and bar at a corner of the sash, and permitting transverse yielding movement of one of said parts, substantially as described.

110

20. A sash having hollow stiles and bars and elbow-shaped connection members uniting said parts at the corners and permitting transverse yielding movement of the latter, substantially as described.

115
